CLAIM

We claim the ornamental design for the pair of handle assemblies for a cross training exercise device, as shown.

DESCRIPTION

FIG. 1 is right side perspective view;

FIG. 2 is a right side elevational view, the left side view being a mirror image thereof.

FIG. 3 is a rear elevational view.

FIG. 4 is a front elevation view.

FIG. 5 is a top plan view; and,

FIG. 6 is a bottom plan view.

The broken line portions of the cross training exerciser are included for the purpose of illustrating environment and form no part of the claimed design.
